WOMAN'S SPORT SHOE

John Henry Schroeder, Portsmouth, Ohio

Application August 19, 1942, Serial No. 455,339

1 Claim. (Cl. 36—12)

This invention is directed to shoe construction and is primarily concerned with the details of construction of a shoe of the molded outsole type, particularly but not exclusively intended for women's sport wear.

The use in footwear of a molded outsole, that is, an outsole formed from a sheet of ordinary sole leather which has an upstanding peripheral flange, has heretofore been limited generally to shoes of the moccasin type and bedroom slippers. However, there are also instances in which this construction has been used in ordinary street shoes, a particular example of this being the patent to Levin and McGee, No. 2,200,068, of May 7, 1940, which discloses a more or less conventional type of shoe in which the molded outsole extends upwardly and forms a part of the upper.

As distinguished from shoes of this type, the present invention contemplates a construction in which the molded outsole extends only to a point approximating the sole line of the foot thereby creating the appearance of what is known in the trade as a "platform" sole.

A platform sole as used in both men's and women's shoes comprises, generally, a plurality of layers of leather and filler superimposed one over the other and intended to provide a very strong and sturdy sole and at the same time to impart to the shoe a somewhat unique and attractive appearance.

The shoe of the present invention resembles a shoe having a platform sole in that the upper commences at a point which is relatively high up on the shoe due to the extra thickness of the sole. However, instead of being formed entirely from a plurality of layers as in a platform sole, the sole contemplated by the present invention is formed from a single piece of molded sole leather having an upstanding flange around the periphery. The interior of this cup-shaped sole is then built up to a level approximately equal to the upper edge of the flange. An upper is then secured to the upper edge of the flange by stitching, lacing or the like.

Another feature of the present invention has been the general adaptation of the molded outsole type of construction to shoes intended for ordinary street wear. To this end the present construction contemplates the lasting of the upper to an insole sheet adapted to reinforce and strengthen the outsole and the provision of separate heel elements which may be interior of or exterior of the molded outsole.

With these general concepts in mind, one of the objects of the invention has been to provide

a shoe which resembles in appearance a shoe having a platform sole but which utilizes a molded outsole having an upstanding flange terminating approximately at the sole line of the foot.

Another object of the invention has been the provision of a two part insole construction comprising a flexible sheet member adapted to reinforce and strengthen the outsole and a cushioning filler member adapted to be superimposed over the sheet member.

Another object has been the provision of a separate heel member which may be positioned interior of the molded outsole.

Another object has been the adaptation of ordinary shoe construction to a shoe of the molded outsole type to provide a shoe which is of unusual and attractive appearance and one which has wearing qualities equal or superior to those of shoes of more conventional construction.

Other and further objects and advantages will be apparent from a consideration of the further and more detailed description of the invention when considered in conjunction with the drawing in which:

Figure 1 is a side elevation of the exterior of a shoe of the type of the invention.

Figure 2 is a longitudinal section through the middle of the shoe illustrated in Figure 1.

Figure 3 is a perspective view of the same shoe particularly illustrating the details of the heel assembly.

Figure 4 is a longitudinal section through a shoe illustrating a slightly modified form of the invention.

In Figure 1 a shoe is indicated generally at 1. This shoe includes a molded outsole 2 which has its upper edge terminating at 3, a point which coincides approximately with the sole line of the foot. The upper is indicated generally at 4 and may be secured to the molded outsole along the upper extremity of the flange by stitching or lacing as illustrated.

The details of the construction of the shoe are best illustrated in Figures 2 and 3 which disclose a preferred form of the invention. In this figure, in addition to the elements illustrated in Figure 1, a two part insole is shown composed of the flexible sheet 6 and the resilient filler member which may be formed in different sections such as 7 and 8. These sections may be joined by metal clips at a central point 10. The sheet 6 may be adhesively secured to the upper surface of the molded outsole and the resilient filler

member 1-8 is superimposed on the sheet and may or may not be secured to it. A conventional sock lining 11 is superimposed on the filler member.

In the heel construction a separate heel member 12 which may be wood is positioned in a pre-formed heel depression in the molded outsole and has a narrow projection 18 extending forwardly over the instep portion of the shoe. This projection provides a substantially level surface on the interior of the shoe and helps to prevent sagging of the instep of the foot. The entire wood heel is held in place by the insole sheet 6 which completely covers it. The top lift 5 may be secured to the heel through the molded outsole by nails such as 13.

In the modified construction shown in Figure 4 a shank iron 14 is utilized in lieu of the forward projecting portion of the heel member 18 shown in Figure 2. This iron has an end resting on the heel 20 and extends forwardly over the instep portion of the shoe. The shank iron may be held in position by the cover 15 which may be of leather and which may be adhesively secured to the heel and the molded outsole. The insole sheet 6 which has been previously assembled with the upper on a last may then be adhesively secured to the shank iron cover and outsole. The cavity formed beneath the shank iron may be filled with any conventional filler 16 which may be cork or leather dust.

In the construction of the shoe generally a molded outsole is first formed by saturating a blank of sole leather and then molding this blank around a last of the desired contours. This operation may be performed mechanically or by hand, or by a combination of both methods. After the leather has dried and hardened the upper edge is trimmed to provide a flange of substantially uniform height around the periphery of the sole. This height may be increased somewhat at the heel portion and, in the form illustrated in Figures 1 and 2, it is desirable that a depression be formed at the rear for the reception of the heel member 12 interior of the molded outsole. The edges of the flange should be skived as shown to provide an improved appearance.

The upper is then lasted to an insole in the conventional way. The margins of the upper may be folded over the lower surface of the insole sheet 6 as illustrated and adhesively secured thereto. The insole sheet may be formed from cloth, leather or compositions and preferably should be of substantial thickness and strength.

In the assembly of the shoe the heel member 12 is fitted into position on the interior of the molded outsole and may be secured there adhesively. The upper and insole assembly is next placed on the interior of the molded outsole. The lower surface of the insole may be secured adhesively to the upper surface of the outsole while the upper may likewise be stitched or laced to the flange of the outsole to provide an improved appearance and additional strength.

Finally, the cushioning insole filler 7-8 may be placed in position and secured there by adhesive or simply held in position by friction. In the form of filler illustrated in Figure 2, the for-

ward element 7 is formed from felt and is intended to be more resilient than the rear element which may be paperboard or the like. This type of construction tends to increase the springiness of the forward part of the shoe although, if desired, the entire member may be formed from felt or some other resilient material.

In the form of the invention shown in Figure 4, the shank iron is of conventional construction and may be placed in position after the heel element 12 and the filler 16 have been positioned and secured on the interior of the molded outsole. In this figure the resilient filler element has been omitted.

It has been found that the provision of a strong resilient insole member and the securing of this member to the interior of the outsole greatly strengthens this type of construction. The provision of the resilient filler member of substantial thickness is likewise an important feature of the invention as its use builds up the interior of the shoe to the level of the flange of the outsole so that the upper part of the foot is covered only by the upper of the shoe and the comfort of the construction is thereby greatly increased. Although the filler member is of generally resilient material such as the felt and paperboard previously mentioned, it has been found that these and other resilient materials have sufficient body to support the upstanding flange of the outsole and maintain it in substantially vertical position with respect to the body of the outsole. Were it not for this support the flange would tend to incline inwardly because of the pull exerted by the upper. Such an inclination would tend to destroy the appearance of the shoe by creating the impression that the flange was a part of the upper rather than the edge of the sole. There is also a structural disadvantage in permitting the flange to flex back and forth as this flexing tends to weaken the molded outsole along the line where the flange joins the base of the outsole. Unless the flange is maintained in substantially rigid position any continuing flexing of this sort may tend to weaken the outsole to a point where moisture and water can enter.

The construction offers opportunities for attractive styling in the contrasting of the material of the upper with the flange of the outsole.

Having described my invention, I claim:

A shoe comprising an outsole molded from sole leather and having an upstanding peripheral flange, said outsole being configurated to provide an arch support portion and having a depression at the rear thereof for the reception of an independent heel element, a rigid heel element positioned in said depression, an arch supporting member extending forwardly from the heel element across the arch support portion of the outsole, an insole positioned on the heel element and outsole, said insole including a resilient filler of substantial thickness contacting and supporting the outsole flange against inward flexing and having its upper surface substantially coinciding with the upper edge of the outsole flange and an upper secured to said flange; said upper holding said outsole flange against outward flexing.

JOHN HENRY SCHROEDER.
